UNITED STATES PATENT OFFICE.

ALLEN DUNTON SPENCER, OF BALTIMORE, MARYLAND, ASSIGNOR OF ONE-THIRD TO RICHARD M. WALLACE, OF SAME PLACE.

TOOL FOR TRUING DYNAMO-COMMUTATORS.

SPECIFICATION forming part of Letters Patent No. 430,094, dated June 10, 1890.

Application filed February 15, 1890. Serial No. 340,524. (No model.)

To all whom it may concern:

Be it known that I, ALLEN DUNTON SPENCER, of the city of Baltimore, and State of Maryland, have invented certain Improvements in Tools for Truing Dynamo-Commun-
5 tators, of which the following is a specifica-
tion.

This invention relates to certain improvements in a tool whereby the faces of dynamo-
o commutators and other rotative cylindrical objects which have become worn may be
trued or brought to an accurate cylindrical
shape while the same is in motion, as will
hereinafter fully appear.

5 The said invention consists in a segmental
toothed block having suitable handles, whereby
the same may be held to the surface to be
repaired.

In the further description of the said in-
o vention which follows reference is made to
the accompanying drawings, forming a part
hereof, and in which—

Figure 1 is a side view of the improved
tool, and Fig. 2 a top view of the same. Fig.
5 3 is an under side view of the invention.

Similar letters of reference indicate similar
parts in all the views.

In the said drawings, A represents a block
having a hollow surface, which is a part of or
o a segment of a circle. This surface, which is
denoted by a, is serrated or toothed after the
manner of a file, and its curvature is made as
nearly as possible to correspond with the cir-
cumference of the object to be trued. The

back b of the block is flat, and to it is secured 35
by means of screws c a bar d, having the han-
dles e at its ends. The length of the block A
is preferably the same as that of the face of
the commutator or object to be filed.

Commutators, if not properly watched and 40
attended to, become grooved and flattened by
the action of the brushes, and they are gen-
erally taken from the machine and turned,
so as to be again true, in a lathe. This op-
eration of course renders the dynamo of no 45
use for the time, and the truing operation is
expensive.

The commutator may be put in complete
order by holding with both hands the device
described against its cylindrical surface until 50
the irregular projections on the same are re-
moved.

The commutator is shown in dotted lines
in Fig. 1 and marked C. One of the handles e
may be thrown up, as shown in dotted lines 55
in Fig. 1, if desired.

I claim as my invention—

A tool for the purpose described, which
consists of a hardened steel block with a seg-
mental toothed face, combined with a bar se- 60
cured transversely of the back of the block,
and a handle at each end of the bar, substan-
tially as and for the purpose specified.

ALLEN DUNTON SPENCER.
